United States Patent Office

Des. 179,501
Patented Jan. 1, 1957

179,501

THERMOSTAT

Bertrand N. Trombley, Birmingham, Mich., assignor to
Detroit Controls Corporation, Detroit, Mich., a cor-
poration of Michigan

Application December 30, 1955, Serial No. 39,530

Term of patent 14 years

(Cl. D52—7)

FIG. 2

FIG. 1

FIG. 3

FIG. 4

FIG. 5

Figure 1 is a front view of a thermostat showing my new design,

Figure 2 is a top plan view of the thermostat,

Figure 3 is a bottom plan view of the thermostat,

Figure 4 is a left end view of the thermostat, and

Figure 5 is a right end view of the thermostat.

The characteristic features of the thermostat reside in the full line portions.

I claim:

The ornamental design for a thermostat, as shown and described.
